UNITED STATES PATENT OFFICE

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY

THREAD-CUTTER OPERATING MECHANISM FOR SEWING MACHINES

Application filed June 27, 1930. Serial No. 464,177.

This invention relates to sewing machines and more particularly to sewing machines of the straight buttonhole type having a stop-motion device for controlling the period of operation of the stitch-forming mechanism and also having an upper-thread nipper and cutter mounted on the work-clamping foot, as represented in the Allen Patent No. 885,310.

With a machine of this character, the stop-motion device must stop the machine with the upper-thread take-up at its highest point, so that, when the machine is again started, the upper- or needle-thread will not be broken or pulled out of the nipper and so that the first stitch will be properly and fully tightened. When the take-up is at its highest point, however, the needle has executed the first part of its down-stroke and, while it has not reached the path of the upper-thread-cutter, there is danger that, as it dips further during the overthrow motion or motion of compression of the usual stop-motion buffer-spring, its point may reach the path of the thread-cutter and be blunted by interference with this cutter which is customarily tripped into action by the up-motion of the stop-plunger into the notch of the stop-cam immediately preceding the overthrow motion or motion of compression of the usual buffer-spring. In other words, in the machine referred to, the needle-thread cutter is executing its closing or thread-cutting and -nipping movement simultaneously with the down movement of the needle permitted by the overthrow or buffer-compressing movement of the machine incident to the operation of the stop-motion device. Hence the danger of interference by the needle in dipping into the path of the thread-cutter.

The present invention has for an object to eliminate the danger of blunting the needle by interference with the upper-thread cutter.

With the above and other objects in view, as will hereinafter appear, the invention consists in the devices, combinations and arrangements of parts hereinafter set forth and illustrated in the accompanying drawings of a preferred form of the invention, from which the several features of the invention and the

advantages attained thereby will be readily understood by those skilled in the art.

In the accompanying drawings, Fig. 1 is a side elevation of a buttonhole sewing machine embodying the invention. Fig. 2 is a horizontal section through the bracket arm standard of the machine, showing the machine-bed in plan. Fig. 3 is a bottom plan view of a portion of the machine-bed. Fig. 4 is a transverse vertical section through the machine bed on the line 4—4, Fig. 2. Fig. 5 is a rear end elevation of the machine. Fig. 6 is a detail view of an element of Fig. 5. Fig. 7 is a disassembled perspective view of the stop-cam and buffer spring mechanism of the stop-motion device. Fig. 8 is a view illustrating the upper thread-cutter tripping mechanism with the parts in their respective positions occupied as the stop-motion plunger enters the notch in the stop-cam and before there is any overthrow or buffer-compressing motion of the machine parts. Fig. 9 is a similar view showing the parts in full lines at the end of the overthrow motion of the machine parts and, in dotted lines, the movement imparted to the needle thread-cutter release mechanism by the recovery or return motion of the buffer mechanism, following the overthrow or buffer-compressing action of the stop-motion mechanism. Fig. 10 is a face view of the needle-bar reciprocating and take-up actuating mechanism, and Fig. 11, is a fragmentary top-plan view of the tension-release mechanism.

The machine illustrated comprises a bed 1, standard 2, overhanging bracket-arm 3 and head 4 in which is journaled the reciprocating and laterally vibrating needle-bar 5 carrying the needle 6. The needle-bar 5 is operated by the usual connections with the main-shaft 7.

Cooperating with the needle 6 below the bed 1 is the usual oscillatory shuttle 8, and the needle-thread loops are drawn up and tightened by means of the usual link take-up 9. As shown in Fig. 10, a take-up of this character comprises a bell-crank lever 9 which at its lower end embraces a crank-pin 10 on the main-shaft 7 and is pivotally connected at 11 to an anchor-link 12. The take-up actuating crank-pin 10 commonly is angularly offset 100

from and lags behind the needle-bar-operating crank-pin 13, so that when the take-up thread-eye 14 is at its highest point, Figs. 1 and 10, the needle-bar 5 has executed the first 5 part of its down-motion.

5 The machine comprises the usual work-clamp including the cross slide-plate 15 in which is mounted the longitudinal slide-plate 16 carrying the fulcrum-support 17 for the 10 upper clamp-lever 18 which at its forward end carries the clamp-foot 19. During the sewing operation the work-clamp is moved over the bed 1 to place the stitches in the desired order or arrangement around the buttonhole 15 by the usual connections (not shown) with the feed-cam-grooves 20' and 20", Fig. 4, in the feed-wheel 20 which is geared to the main-shaft 7 and makes one complete revolution per buttonhole-producing cycle.

20 Mounted in the upper clamp-foot 19 on the short vertical shaft 21 are the usual needle-thread cutter and nipper blades 22 which are arranged to sweep horizontally across the needle-path or lead of the needle-thread at 25 the close of a sewing period to cut and hold the needle-thread in the manner disclosed in said Allen Patent No. 885,310. The shaft 21 carries a crank-arm 23 to which is pivotally connected a bar 24 slidably supported 30 near its rear end in the bracket 25 and energized by the spring 26, Fig. 2, to close the thread-cutter and nipper blades. When sewing down the return side of the buttonhole, the rod 24 which is moving endwise of 35 itself in a rearward direction encounters the usual latch-arm 27 and has its motion arrested while the continued rearward motion of the work-clamp opens the thread-cutter. When the sewing is completed, the parts are in the 40 positions shown in Fig. 2 and the thread-cutter 22 is held open by the latch-arm 27 which is fixed to the horizontally disposed rock-shaft 28 mounted at one side of the standard 2 and common to machines of this type. Act- 45 ization of the rock-shaft 28 will therefore serve to raise the latch-arm 27 to dotted line position, Fig. 4, and release the needle-thread cutter 22.

The rock-shaft 28 also has fixed thereto the 50 bent arm 29, Figs. 1 and 4, the forked front end of which embraces the rearward end of the arm 30 fixed to the tension-release rock-shaft 31 carrying the wedge-pointed arm 32, Fig. 11, for releasing the drag of the tension-device 33 upon the needle-thread. The wedge-pointed arm 32 is arranged close to the tension-disks 33 so that, when the rock-shaft 28 is operated, the tension-device will 55 be opened before the thread-cutter and nipper 22 is released, whereby slack needle-thread is provided to be drawn by the movable cutter and nipper blades 22 into nipped position between such movable blades and the usual stationary upper nipper member (not shown) common to a thread-cutter and

6 nipper of this type, as shown in said Allen Patent No. 885,310.

70 Mounted loosely on the rock-shaft 28 is a bell-crank lever 34, 35, the arm 34 of which extends downwardly through an aperture 36 in the bed 1 and is connected as usual to actuate the under-thread cutter and pull-off operating lever 37, substantially as shown in said Patent No. 885,310. The arm 35 of the bell-crank lever has an aperture at its free end 75 for connection with the usual pedal-operated clamp-lifting chain (not shown). There is also connected at 38 to the bell-crank lever arm 35 a vertical rod 39 which is guided at its lower end in the bracket 40 and carries the work-clamp lifting roller 41 disposed above and adapted to depress the tail 18' of the upper work-clamp lever 18 to raise the clamp-foot 19 for release of the work. The vertical rod 39 has a notch 42 in one side 80 adapted to be entered by one end of the locking lever 43 the other end of which is formed with an upstanding lip 44 in the path of movement of the lower end of a curved arm 45 fixed to the rock-shaft 28. When the machine is sewing, the lever 43 is in the notch 42 of the rod 39 and the bell-crank lever 34, 35 is locked against movement by the operator. It is unlocked by the same rocking movement 85 of the shaft 28 which releases the needle-thread-cutter and opens the tension-device.

90 The stop-motion device for controlling the period of operation of the stitch-forming mechanism is preferably constructed substantially in accordance with the disclosure of the Allen and Myers application, Serial No. 272,416, filed Apr. 24, 1928. The main-shaft 7 has fixed to it the gear 46 which drives the gear 47 at half speed. The shaft 7 also carries the usual tight and loose belt-pulleys 48, 49, respectively. The gear 47 constitutes 100 a housing for the buffer-springs 50, 51 disposed between the abutment 52 fixed within and to the gear 47 and the block 53 disposed within and relative to which the gear 47 is 105 free to move to a limited extent. The block 53 is connected to the pin 54 on the stop-cam 55 loose on the bearing stud 55' on which the gear 47 is journaled.

110 Cooperating with the stop-cam 55 is the usual vertically spring-pressed plunger 56 mounted in the tilting stop-motion lever 57 which includes the usual belt-shipper arm 58. The present stop-cam 55 is of duplex construction, that is, it has two diametrically 115 opposed stop-notches 59 and two plunger-depressing eccentric portions 60. The stop-motion lever 57 is held in its tilted or running position, Fig. 1, by the usual feed-cam-controlled latch-lever 61 which enters a notch 61' in the side of the vertically spring-pressed latch-rod 62 connected at its upper end to the arm 63 rigid with the stop-motion lever 57. When the tripping point 64 on the feed-cam 20 trips the latch 61, the stop-motion lever 120 125 130

57 will spring to its vertical or dotted line position, Fig. 1, in which position the upper end of the plunger bar 56 will be engaged by one of the eccentric portions 60 of the stop-cam 55 and depressed, after which the plunger-bar 56 will be projected upwardly by its spring into the succeeding stop-notch 59 and arrest further movement of the cam 55.

The main-shaft 7 of the machine and the parts connected thereto and driven thereby have momentum at this time and, to avoid excessive shock, provision is made for an overthrow or momentum absorbing motion of the main-shaft and gear 47 after the stop-cam is locked in stopping position by the stop-motion plunger 56. This overthrow motion of the gear 47 causes the abutment 52 to compress the buffer-spring 51 against the then stationary abutment-block 53. Following the overthrow motion of the gear 47 is a recovery motion of said gear in a reverse direction to the final stopping position or position of rest of the main-shaft 7.

According to the present improvement, advantage is taken of this reverse or recovery motion of the parts following the overthrow or buffer-compressing motion of the main-shaft and connected parts to trip the upper or needle-thread cutter, open the tension device, unlock the work-clamp or perform any desired operation auxiliary to the sewing operation, the time of which auxiliary operation it may be desirable to delay as late as possible in a buttonhole producing cycle.

To this end a novel mechanism actuated by the recovery motion of the gear 47 is provided for imparting a rocking impulse to the shaft 28 which heretofore has customarily been rocked by the up-motion of the plunger bar 56 into the stop-notch of the usual stop-cam. Fixed to the rear end of the rock-shaft 28 is the arm 65 having pivoted thereto at 66 a follower element comprising a lever 67 the upper end of which is formed with a hook-shoulder 68 disposed in the plane of the actuator cam-plate 69 which is fixed by screws 70 passing through arcuate slots 71 in the cam-plate 69 to the cover-plate 72 for the buffer-spring cavity in the gear 47; the cover-plate 50 being screwed to the internal hub 73 of the gear 47. The cam-plate 69, which is thus a fixed part of the gear 47, is formed with diametrically opposed shoulders 74 with one or the other of which the hook-shoulder 68 operates on the recovery motion of the gear 47 to rock the shaft 28.

The lever 67 which is normally urged toward the cam-plate 69 by the spring 75 is held in retracted or inactive position, out of engagement with the cam-plate 69, Figs. 2 and 5, by the side pressure thereagainst of the head 76 of the pin 77 fixed to the tilting stop-motion lever 57. When the stop-motion lever 57 springs to vertical or stopping position, the head 76 of the pin 77 is carried out

of engagement with the lever 67 which is free to be swung by its spring 75 into the reduced neck 78 of the pin 77, whereby the upper end of the lever 67 is carried into engagement with the edge of the cam-plate 69, as shown in Fig. 8.

The shoulders 74 are so timed on the gear 47 that when one of the stop-notches 59 of the stop-cam is engaged by the stop-motion plunger 56, at which time the overthrow or buffer-compressing motion of the parts begins, one of the stop-shoulders 74 will be near the hook-shoulder 68 on the lever 67, as shown in Fig. 8. At this time, the take-up 9 is at its highest point and the needle 6 has executed the first part of its down-stroke and is moving downwardly under the momentum or buffer-compressing or overthrow-motion of the parts. Just before this overthrow-motion is completed, the shoulder 74 is carried past the hook-shoulder 68 which latter moves inwardly or hooks over the shoulder 74, as shown in Fig. 9, which represents the parts at the end of the overthrow motion or the beginning of the reverse or recovery motion, during the execution of which recovery motion the needle of the sewing machine is moving upwardly or away from the path of the needle-thread cutter and the arm 65 is being lifted to dotted line position and imparts the desired rocking impulse to the shaft 28.

When the recovery motion is spent, the main-shaft 7 will have returned to the same position it occupied when the stop-motion plunger 56 first entered one of the stop-cam notches 59. The take-up will be at its highest point. During the last part of the rocking movement of the shaft 28, the latch 27 is raised out of engagement with the needle-thread cutter-control rod 24, thereby releasing said rod at a time when the needle is moving upwardly or away from the needle-thread cutter and when all danger of interference between the needle and thread-cutter is past. The line *a*, Fig. 8, represents the position of the main-shaft when the take-up 9 is at its highest point and when the plunger 56 first engages the stop-notch 59. The line *b*, Fig. 9 represents the position of the main-shaft at the end of its overthrow motion and the line *c* represents the position of the main-shaft at the end of its recovery motion; lines *c* and *a* being in the same vertical position.

By virtue of the slots in the plate 69 through which the screws 70 pass, said plate may be adjusted circularly relative to the gear 47 to insure that one of the shoulders 74 will be carried past the hook-shoulder 68 at the end of the overthrow motion of such gear.

The tension-release arm 32 is timed to release the tension before the thread-cutter is tripped, so that free needle-thread will be supplied to be carried into the nipper associated with the thread-cutter.

The work-clamp lock-lever 43 will also be moved to unlocking or dotted line position, Fig. 2, by the recovery motion of the main-shaft 7 and gear 47, so that the usual manually operated work-clamp-lifting and under thread-cutter-operating lever 35 cannot be actuated while there is danger of interference with the moving needle.

Means are preferably provided to insure the closing of the work-clamp prior to starting the machine. To this end there is connected to a lateral-arm 57' on the stop-motion lever 57 one end of a link 79 the other end of which is connected to a lever 80 fulcrumed at 81 on the machine-bed and having an angular arm 82 extending back of the lever-arm 34, Fig. 2, which is rigid with the manually operated clamp-lifting arm 35. When the stop-motion lever 57 is tilted to running or full line position, Fig. 1, the link 79 pulls on the lever 80 forcing its arm 82 against the side of the lever-arm 34 and forcing the lever 35 upwardly to lower the work-clamp.

The cam-incline 78' between the neck 78 and head 76 of the pin 77 serves to retract the lever 67 from the cam-plate 69 when the stop-motion lever 57 is shifted to running position. This motion releases the rock-shaft 28 which thereupon moves to restore the tension on the thread and allow the clamp-locking lever 43 to enter the notch 42 in the vertical rod 39.

While the invention is shown as embodied in a machine having the stop-motion mechanism of the Allen and Myers application, referred to, I do not find it necessary to confine the invention to that exact mechanism. The invention is obviously adaptable to any form of stop-motion mechanism, the operation of which involves a retrograde motion of certain parts immediately preceding the final stoppage of the machine.

Having thus set forth the nature of the invention, what I claim herein is:

1. A sewing machine having stitch-forming mechanism, a main-shaft, a stop-motion device including means for imparting a retrograde motion to the main-shaft before bringing it to a final rest, a thread-cutter, and means actuated by an element of the machine in the retrograde motion of the parts for operating said thread-cutter.

2. A sewing machine having stitch-forming mechanism, a main-shaft, a stop-motion device including a resilient buffer for absorbing the momentum of the machine in bringing it to rest, a needle-thread cutter, and means actuated by an element of the machine in the recovery motion of the parts succeeding the buffer-compressing motion for operating said thread-cutter.

3. A sewing machine having stitch-forming mechanism including a reciprocating needle, a main-shaft, a needle-thread tension device, a needle-thread cutter and nipper, a

stop-motion device including a resilient buffer for absorbing the momentum of the machine parts and imparting a reverse motion to said parts before bringing the machine to a final position of rest, and means actuated by an element of the machine in the reverse motion of the parts for first releasing the tension-device and then operating the needle-thread cutter and nipper.

4. A sewing machine having in combination, stitch-forming mechanism including a reciprocating needle, a work-clamp, a needle-thread take-up timed to be at its highest point after the needle has executed the first part of its down-stroke, a needle-thread cutter mounted on said work-clamp to cross the path of the needle, a main-shaft, a stop-motion device including means for imparting a retrograde motion to the main-shaft before bringing it to a final rest with the take-up at its highest point, and means actuated by an element of the machine in the retrograde motion of the parts for operating said thread-cutter.

5. A sewing machine having, in combination, stitch-forming mechanism, a main-shaft, a stop-motion device including a stop-cam and gear connected to the main-shaft to run at a reduced speed and a resilient buffer between said stop-cam and gear to absorb the momentum of the machine parts and impart a reverse motion thereto before bringing the machine to a final position of rest, a needle-thread cutter crossing the path of the needle, and means actuated by said buffer-spring in the reverse motion of the parts for operating said thread-cutter.

6. A sewing machine having a frame including a bed, an upright standard and overhanging bracket-arm, stitch-forming mechanism, a work-clamp, a main-shaft disposed within said bracket-arm and connected to operate said stitch-forming mechanism and work-clamp, a stop-motion device applied to the rearward end of the main-shaft and including tight and loose pulleys, a belt-shipper, a stop-cam, a stop-plunger and buffer means between the stop-cam and the main-shaft operating to absorb the momentum of the machine and impart a reverse motion to the parts in bringing the machine to a final position of rest, a rock-shaft mounted externally of and alongside said standard, means auxiliary to the sewing operation connected to be operated by said rock-shaft, and means controlled by the operation of said stop-motion device for actuating said rock-shaft by the reverse motion of the parts following the buffer-compressing motion.

7. In a sewing machine, stitch-forming mechanism, a stop-motion device for controlling its period of operation, said stop-motion device having a stop-cam, a tilting stop-motion lever having running and stopping positions, a stop-plunger carried by said lever for cooperation with said stop-cam, a buffer-

spring for absorbing the momentum of the machine and imparting a retrograde motion to the parts in bringing the machine to a final position of rest, a shouldered element running with the main-shaft, a rock-shaft, an element connected to said rock-shaft and adapted to be operated by said shouldered element in the retrograde motion of the main-shaft following the buffer-compressing motion, means on the tilting stop-motion lever for holding said last mentioned element out of range of said shouldered element while the stop-motion lever occupies running position, and means auxiliary to the sewing operation connected to be operated by said rock-shaft after the sewing operation is completed.

8. An automatic sewing machine having, in combination, stitch-forming mechanism, a work-clamp, a stop-motion device for bringing the stitch-forming mechanism to rest at a predetermined position in a stitch-forming cycle, said stop-motion device including co-acting stop-elements and buffer-means for absorbing the momentum of the machine parts, said buffer means operating to impart a reverse motion to the machine parts following its momentum absorbing action, a follower-element adapted to be actuated by one of said machine parts during the reverse motion, means connected to the stop-motion device for holding said follower-element out of engagement with its actuator during the sewing operation, and means operated by said follower-element for performing a desired operation subsequent to the sewing operation.

9. A sewing machine having stitch-forming mechanism, a main-shaft, a stop-motion device having a tilting stop-motion lever, a stop-cam running with said main-shaft, a stop-plunger carried by said stop-motion lever, a buffer-spring interposed between said stop-cam and main-shaft, whereby the main-shaft has a buffer-compressing motion followed by a reverse motion, a rock-shaft and connections for performing a desired operation subsequent to the sewing operation, a rock-shaft actuator running with the main-shaft, a follower connected to said rock-shaft and adapted to engage said actuator, and means mounted on said stop-motion lever and formed with a cam-portion for controlling the motion of said follower into and out of engagement with said actuator, said actuator comprising an element having a shoulder arranged to move said follower only during the reverse motion of the main-shaft following the buffer-compressing motion.

In testimony whereof I have signed my name to this specification.

EDWARD B. ALLEN.
